[57] CLAIM

The ornamental design for a dual male pin connector, substantially as shown and described.

DESCRIPTION

FIG. 1 is a perspective view of the dual male pin connector showing my new design;

FIG. 2 is a perspective view thereof with a mating component shown in broken lines for illustrative purposes only;

FIG. 3 is a left side elevational view thereof;

FIG. 4 is an enlarged fragmentary side elevational view thereof taken along the circle 4 of FIG. 3;

FIG. 5 is a front elevational view thereof;

FIG. 6 is an enlarged fragmentary rear elevational view thereof taken along the circle 6 of FIG. 5;

FIG. 7 is a right side elevational view thereof;

FIG. 8 is a rear elevational view thereof;

FIG. 9 is an end elevational view thereof;

FIG. 10 is an opposite end elevational view thereof.

The pins are partially depicted in FIGS. 3, 5, 7 and 8 for convenience of illustration only.
